UNITED STATES PATENT OFFICE.

LEWIS J. BAZZONI, OF SWAMPSMOTT, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

BUTTONING-MACHINE.

1,273,443.

Specification of Letters Patent. Patented July 23, 1918.

Application filed June 13, 1916, Serial No. 103,446. Renewed March 26, 1918. Serial No. 224,887.

To all whom it may concern:

Be it known that I, LEWIS J. BAZZONI, a citizen of the United States, and resident of Swampscott, in the county of Essex and State of Massachusetts, have invented certain Improvements in Buttoning-Machines, of which the following description, in connection with the accompanying drawings, is a specification, like reference characters on the drawings indicating like parts in the several figures.

This invention relates to buttoning machines, and is herein shown as embodied in a machine particularly adapted for use in the manufacture of boots and shoes for buttoning, in accordance with the usual practice, several of the buttons of the shoe upper prior to the assembling and lasting operations in order to facilitate the proper lasting of the shoe and to insure that the button piece and the buttonhole fly shall be correctly positioned in the finished shoe. It should be understood, however, that the invention, in many of its features and in its broader aspects, is not limited in utility to machines for buttoning shoes nor restricted to the precise embodiment herein illustrated, but is susceptible of various embodiments and applicable to various uses upon different classes of work.

It will also be apparent from a consideration of the drawings and description that the illustrative machine may be used with equal facility for performing buttoning operations upon finished shoes as well as for buttoning the upper materials of a shoe before the shoe is lasted.

The invention is herein illustrated as embodied in a machine for buttoning a plurality of buttons simultaneously, but it will be apparent from a consideration of the construction and mode of operation of various portions of the illustrative machine that in many of its aspects the invention is not limited to a machine of this particular type.

An object of the invention is to provide a buttoning machine of simple construction in which the work may be quickly arranged in position for buttoning and which will perform the buttoning operation in a rapid and effective manner.

Important features of the invention reside in novel means for effecting relative movement between a button and the material adjacent to a buttonhole to perform a buttoning operation with respect to the button. The construction shown provides buttonhole fly engaging means constructed and arranged for wiping engagement with the material at opposite sides of a buttonhole to effect a progressive movement of the material into buttoned position, said means, in the illustrative construction, being movable longitudinally of the buttonhole.

A further feature of the invention consists in novel means for insuring the disposal of the material adjacent to a buttonhole in buttoned position under the head of a button. For this purpose the invention, in its illustrative embodiment, provides buttoning means for forcing the material adjacent to a buttonhole under the head of a button and means for positioning the button in such manner as to permit it to be lifted by the buttoning means. The construction shown comprises means movable relatively to the material of the buttonhole fly to press it toward buttoned position and to lift the button to facilitate the disposal of the material under the edges of the button head.

Another feature of the invention consists in novel means for opening a buttonhole for the reception of a button, the construction shown comprising means movable longitudinally of the buttonhole in spreading engagement with the material at the edges of the buttonhole.

The above and also other features of the invention, residing particularly in novel work positioning and work ejecting means and in various novel details of construction and combinations of parts, will now be described with reference to the accompanying drawings and pointed out in the claims.

In the drawings,

Figure 1 is a view in side elevation and partly in vertical section of a machine in which the invention is embodied, the coöperating parts of the machine being shown in their initial or starting positions with an article such as a shoe upper in position to be buttoned;

Fig. 2 is a top plan view of the machine

shown in Fig. 1, with portions broken away in order to illustrate the construction more clearly;

Fig. 3 is a view partly in elevation and partly in vertical section showing more in detail a portion of the mechanism seen in Fig. 1;

Fig. 4 shows one of the buttoning members in rear elevation;

Fig. 5 is a vertical section on the line 5—5 of Fig. 4;

Fig. 6 is a bottom view of the buttoning member seen in Fig. 4;

Figs. 7, 8 and 9 are views in vertical section through a portion of the mechanism, illustrating successive stages in a buttoning operation;

Fig. 10 is a view in side elevation of the mechanism seen in Fig. 7 at the same stage in the buttoning operation, and

Fig. 11 is a detail of a portion of the mechanism for operating a work clamp with which the machine is provided.

The machine comprises a plurality of sets of coöperating instrumentalities, each set including button and button-hole fly positioning means and a buttoning device. Each set has its own independent support, and the several supports are mounted for relative movement to conform to differences in the spacing of buttons and buttonholes on different pieces of work. In the machine shown there are five sets of instrumentalities, in order to adapt the machine for buttoning five buttons at each presentation of a piece of work, but it will be understood that the machine may include any suitable number of sets, according to the number of buttons which it may be desired to button.

A base or frame on which the operating mechanism is mounted is indicated at 10 and an operating shaft at 11, the frame being provided with bearings for the shaft. A plurality of adjustable button positioning members are indicated at 12, these members comprising forwardly directed forks for the reception of the buttons when the work is initially presented to the machine. Each of the members 12 is secured to a separate arm 13, and the several arms are pivotally mounted upon an upright rod 14 secured in the frame 10. As shown by Fig. 1, each arm 13 has two separate portions embracing the rod 14. The two portions of one arm are indicated at 13^a, those of another arm at 13^b, those of the third arm at 13^c, and those of the fourth at 13^d. The fifth or central button positioning fork is indicated at 12^x in Fig. 2. This fork, as distinguished from the forks 12, is fixed in position, being secured directly to the frame 10. The fixed fork is the middle fork of the series of five, and in consequence of this arrangement the relative adjustment of the several forks is simplified.

The forks 12 and 12^x, as clearly shown in Figs. 1, 7, 8 and 9, receive the shanks of the buttons and support the buttons and the button piece. On the drawings a button is indicated at *a* and the shank at *a'*, the shank being secured by a staple *b* to the button piece *c* of the shoe, garter or other article. The buttonhole fly is indicated at *d*, and a buttonhole at *d'*.

Each member 12 or 12^x is slotted, as shown by Fig. 2, to receive a buttonhole fly positioning member 16. Each of the members 16 has an upwardly extending point 16^x adapted to engage in a buttonhole, as shown by Fig. 1, to determine the position of the buttonhole in relation to the corresponding button. Each member 16 is in the form of a bell-crank and is pivoted at 17 on the member 12 or 12^x. The downwardly extending arms of the several members 16 are all engaged by a single operating lever 18, the latter having for this purpose elongated parallel confronting surfaces 18^x. As the adjustable elements move toward or from each other, the downwardly extending arms of the members 16 slide freely along the surfaces 18^x and remain always in cooperative relation to these surfaces. The lever 18 is mounted upon a fulcrum stud 19 and is oscillated by a path cam 20 secured to the shaft 11 (Fig. 3). A roll 21 carried by the lever 18 engages the cam.

The members 16 are in operative position only for a brief time at the beginning of a cycle of operations. Their function is to determine the position of the buttonhole fly, and such position having been determined, the first operation of the machine is to depress a clamp member which coöperates with the button supporting forks to clamp the buttonhole fly. The clamp member comprises a work-engaging bar 22 which is supported by arms 22^x, one of said arms being broken away in Fig. 1. The two arms are secured to a rockshaft 23 which has an arm 24 operated by a cam 25. The cam does not act directly upon the arm 24 but upon an arm 26 which is loosely mounted upon the rockshaft, and the arm 26 acts through a spring 24^x to apply yielding clamping pressure to the clamping device. The points 16^x remain in the buttonholes until the clamping bar has clamped the buttonhole fly upon the button supporting members, as shown by Fig. 10, the points being thereafter withdrawn from the buttonholes. The points 16^x remain depressed throughout the buttoning operation and until the work is removed, and are then raised to their initial positions to receive the next piece of work.

The several buttoning devices, hereinafter described in detail, are carried by bell-crank levers 27. Each adjustable arm 13 has an overhanging extension upon which is mount-

ed a corresponding lever 27, and the bell-crank lever of the middle buttoning device is supported by a stationary overhanging arm which is secured to the base 10.

5 The several bell-crank levers 27 are mounted in their respective overhanging arms by pivot studs 28. The bell-crank levers are all operated in unison by a single operating lever 29 which has elongated parallel confronting faces 29^x, the members 27 being 10 free to slide from side to side between the surfaces 29^x in the same manner as the members 16 relatively to the lever 18. The operating lever 29 is substantially U-shaped, its two arms being connected by a hub 15 mounted upon a fulcrum rod 30, and a third arm 31 is secured to the hub and operated by a cam 32, Fig. 3, this arm having a roll 33 which engages the cam. The direction 20 of operative movement of the buttoning devices is indicated by an arrow in Fig. 1.

The structural details of one of the buttoning devices are best shown by Figs. 4, 5 and 6. Each device comprises a toe portion 35 which is shaped to enter a buttonhole at the beginning of the operation of the device. This portion engages the material at the end of the buttonhole, as shown by Fig. 10, thus insuring the correct relation of the buttonhole to the button in order to facilitate the operations which follow. The head of the button at this time rests upon the opposite sides of the button supporting fork, being held firmly thereon by the weight of the button piece, and the shank α' is seated against the crotch of the fork between the closely adjacent opposite side portions of the fork so that the button will not be displaced laterally to any material extent by the buttoning device. The buttoning device, as a whole, is in the nature of a cam and has a wiping action upon the stock. Two diverging flanges 36 extend backwardly from the portion 35, as shown by Fig. 6. These flanges enter the buttonhole, and engaging the side edges of the latter exert a wedging action whereby the sides of the buttonhole are separated beyond the edges of the button head, as shown by Fig. 8. The toe portion 35, after drawing the buttonhole fly over the button as hereinbefore explained, becomes disengaged from the material in consequence of downward movement of the latter which is effected 55 both by an inclined front edge of the toe 35 and by cam shoulders 37 outside the flanges 36, said shoulders being inclined relatively to the path of movement of the buttoning device, as shown by Figs. 1, 5 and 10. A

60 passageway 38 is formed in the buttoning device to receive the head of the button while the buttoning device is operating. The rear ends of the flanges 36 are flanged laterally, as at 36^x, the inner edges of the 65 flanged portions being constructed to pass

under the head of the button and lift the button head from the button supporting fork.

The heel of the buttoning device comprises flanges 39 which are, in effect, extensions of the flanged portions 36^x, and which

70 pass under the head of the button as shown by Fig. 9. The buttoning device, as shown,

is made in two parts, the front part being distinct from the rear part. This is to en-

75

able one part to be adjusted relatively to the other, as hereinafter explained; but the principle of operation of the device would

75 be the same if both parts were formed integral. In the device as shown, referring

80

especially to Fig. 5, the rear end of the front or toe part abuts against the forward end of the rear or heel part as indicated at

85 40, the bottom surfaces of the two parts being flush at this point and presenting, to

all intents and purposes, excepting that of adjustment, a continuous structure from the front of the toe to the rear of the heel.

While the flanges 36 of the toe part are opening the buttonhole, the shoulders 37 de-

90

press the material at the edges of the buttonhole below the edges of the button head, thus clearing a path for the flanged portions

95 36^x and flanges 39 to pass between the head of the button and the button piece and lift

100 the button, as shown by Fig. 9. The bottom surfaces of the flanges 39 offer no obstruction to the closing of the buttonhole, the buttonhole automatically closing under the

105 head of the button in consequence of the tendency of the stock to resume its normal condition.

While the stock would normally close under the head of the button if the flanges 39 were omitted, their use is prefer-

110 able in order to insure the proper operation of the device under all conditions. While the flanges 39 underlie and support the head of the button the operative stroke of the

buttoning device ceases and the return stroke begins, the head of the button being thus

115

held elevated for a sufficient length of time to insure the closing of the buttonhole thereunder.

The flanges 39 are substantially concentric in relation to the axes of the respec-

120 tive pivots 28, and are not disturbed when the toe piece is adjusted as hereinafter ex-

125 plained.

The purpose of the adjustment of the front or toe part of the buttoning device is to adapt the device to the particular height

120 of the button head. A button which has a relatively high head requires a greater de-

pressing movement of the buttonhole fly than a button which has a relatively low

125 head, and in order that the toe part of the device may properly enter the buttonhole on the top of the button head, it must be ad-

130 justed in accordance with the height of the head. As shown by Fig. 4, the toe piece is formed with oppositely projecting flanges

41 which are arranged to slide in complementary grooves 42 formed in the member 27. These flanges and grooves are segmental, being concentric to the meeting point 40 of the toe and heel portions. In consequence of this arrangement it is obvious that the rear end of the toe portion will merely rock upon the forward end of the heel portion without causing any separation at said point when the flanges 41 slide forward or backward through the grooves 42. The effect of such sliding movement is to raise or lower the toe 35 relatively to the heel and to vary the inclination of the bottom surfaces 15 of the toe member to cause more or less depressing movement of the material.

Any suitable means may be provided for giving the desired adjustment to the toe piece. I have shown for this purpose a nut 43 threaded upon a shank 44 carried by the member 27. The toe piece has an extension 45 which has co-operative lips 46, the latter embracing the rim of the nut 43 and being movable forward and backward in accordance with the endwise movement of the nut upon the shank.

In determining the necessary adjustment of the toe piece, an article to be buttoned will be presented to the machine as shown by Figs. 1 and 10. The level at which the buttonhole fly is supported will depend upon the height of the head of the button. The toe piece will then be adjusted so that its forward extremity will clear the top of the button and engage in the end of the buttonhole, as shown by Fig. 10.

The machine is provided with an ejector which discharges the work automatically after the buttoning operation has been completed, this ejector comprising a substantially U-shaped member the two arms of which are indicated at 47, one of said arms being partly broken away in Fig. 1. The two arms are connected by a crossbar 48 which underlies all the button supports. The ejector is mounted upon a rockshaft 49 which is operated by a cam 50 through an arm 51, the latter having a roll 52 which engages the cam. The crossbar 48 lies behind the shanks or eyes of the buttons and overlies the button piece *c*, the arms 47 being separated far enough to admit the work between them. The crossbar 48 is thrown forward by the action of the cam and engages the shanks of the buttons or the fastening staples *b*, or both, or on some classes of work engages the button piece adjacent to the buttons, and ejects the work in consequence of such engagement and movement.

When the work is presented to the machine the shanks of the buttons will readily enter the several button supporting forks, the openings in the forks being relatively wide at their forward ends and narrowing

toward the rear. The several arms 13 are free to move about the pivot 14 and will automatically assume the desired spacing in accordance with the spacing of the buttons as the buttons engage the sides of the forks. 70 Any suitable means, not herein shown, may be used if desired to insure that the several sets of operating instrumentalities shall be spaced equidistantly in all positions of adjustment. The points 16* will partake of 75 the adjusting movement of the arms 13 and will therefore be in position to register with the several buttonholes. The buttonhole fly having been positioned by the points 16*, as shown by Fig. 1, the work is ready for the 80 operation of the machine. The first operation is that of the clamping device 22, the latter descending until the buttonhole fly is clamped upon the button supports 12 and 12* to hold the fly against the drag or pull 85 of the buttoning devices. The points 16* descend in time to clear the buttoning devices, but they are not withdrawn from the buttonholes until the buttonhole fly has been clamped. The cam 32 then operates the buttoning devices, the latter being immediately retracted when they have completed their buttoning movement. The clamping device 22 is then raised to release the article, and the ejector 48 is operated. When the article has been ejected, the points 16* are 90 raised to their initial positions and the ejector is also returned to its initial position. All the elements are thus restored to their starting positions and the machine is 95 ready to receive another piece of work.

Having described the invention, what I claim as new and desire to secure by Letters Patent of the United States is:

1. A buttoning machine having, in combination, means for positioning a button, and buttonhole fly engaging means movable laterally of the button head and relatively to the fly to dispose the material adjacent to opposite sides of a buttonhole in buttoned 105 relation to the button.

2. A buttoning machine having, in combination, means for positioning a button, and buttonhole fly engaging means movable in wiping engagement with the material adjacent to a buttonhole while the button is restrained substantially from lateral movement to dispose said material in buttoned 115 relation to the button.

3. A buttoning machine having, in combination, means for positioning a button, and buttonhole fly engaging means movable longitudinally of a buttonhole and constructed to dispose the material adjacent to opposite sides of the buttonhole in buttoned 120 relation to the button through said movement.

4. A buttoning machine having, in combination, means for positioning a button, and buttonhole fly engaging means movable longitudinally of a buttonhole and constructed 125

to open the buttonhole and depress the material at the edges of the buttonhole relatively to the head of the button through said movement.

5 5. A buttoning machine having, in combination, means for positioning a button, and buttonhole fly engaging means movable longitudinally of a buttonhole in wiping engagement with the material at opposite sides 10 of the buttonhole to dispose said material in buttoned relation to the button.

6. A buttoning machine having, in combination, means for relatively positioning a button and a buttonhole fly, and buttonhole 15 fly engaging means movable laterally of the button head into engagement with the fly and also relatively to the fly to dispose the material adjacent to a buttonhole in buttoned relation to the button.

20 7. In a buttoning machine, coöperating instrumentalities relatively movable to perform a buttoning operation with respect to a button and a buttonhole fly, said instrumentalities comprising means movable longitudinally of a buttonhole to open the buttonhole for the reception of the button.

8. In a buttoning machine, the combination with button positioning means, of buttonhole fly engaging means having diverging surfaces for engagement with the material at the edges of a buttonhole to open the buttonhole upon relative movement of said engaging means and the buttonhole fly longitudinally of the buttonhole.

35 9. In a buttoning machine, the combination with button positioning means, of buttonhole fly engaging means constructed to enter and open a buttonhole upon relative movement of said engaging means and the buttonhole fly longitudinally of the buttonhole, said fly engaging means having also portions shaped for engagement with the face of the buttonhole fly at opposite sides of the buttonhole.

40 10. A buttoning machine having, in combination, means for positioning a button, and buttonhole fly engaging means movable laterally of the button head and having a buttonhole fly engaging surface elongated on an incline to the direction of movement of said means for depressing relatively to the button head the material adjacent to a buttonhole.

45 11. A buttoning machine having, in combination, means for positioning a button, means for engaging the material at the edges of a buttonhole and moving said edges in opposite directions beyond the edges of the button head, and means for depressing said material relatively to the button head and disengaging the material from said separating means while the edges are thus separated.

50 12. A buttoning machine having, in combination, means for positioning a button,

and buttoning means movable in wiping engagement with a buttonhole fly to perform a buttoning operation with respect to the button, said buttoning means having surfaces inclined to its direction of movement 70 for opening the buttonhole and for depressing relatively to the button head the material adjacent to the buttonhole.

13. A buttoning machine having, in combination, means for positioning a button, 75 and a buttoning device movable relatively to a buttonhole fly in engagement with the material adjacent to a buttonhole to perform a buttoning operation, said device having means for opening the buttonhole and means 80 for depressing said material relatively to the button head.

14. A buttoning machine having, in combination, means for relatively positioning a button and a buttonhole fly, and a button- 85 toning device movable longitudinally of a buttonhole and having means for opening the buttonhole progressively during said movement and for simultaneously depressing relatively to the button head the material at the 90 sides of the buttonhole to dispose said material in buttoned relation to the button.

15. A buttoning machine having, in combination, means for positioning a button, and a buttoning device movable longitudinally of a buttonhole in wiping engagement with the material adjacent to the buttonhole, said device having means for opening the buttonhole and for depressing said material relatively to the button head through 100 said movement.

16. A buttoning machine having, in combination, means for relatively positioning a button and a buttonhole fly, and a buttoning device movable longitudinally of a buttonhole and having means for depressing relatively to the button head the material at the edges of the buttonhole and means for engagement under the button head to complete the buttoning operation. 110

17. A buttoning machine having, in combination, means for relatively positioning a button and a buttonhole fly, and a buttoning device having means for opening a buttonhole and for depressing relatively to the 115 button head the material at the edges of the buttonhole and also means for engagement under the button head to complete the buttoning operation.

18. A buttoning machine having, in combination, means for relatively positioning a button and a buttonhole fly, and a buttoning device movable laterally over the button head in wiping engagement with the buttonhole fly, said device having diverging surfaces for engagement with the material at the edges of a buttonhole to open the buttonhole and portions shaped to depress the material relatively to the button head, the device having also flanges to slide under the 125 130

button head to complete the buttoning operation.

19. A buttoning machine having, in combination, means for positioning a button, 5 and a buttoning device having means for separating the material at opposite edges of a buttonhole and means for lifting the button in the buttonhole to facilitate the disposal of said material under the edges of 10 the button head, said device being constructed to release said material while the button is in lifted position.

20. A buttoning machine having, in combination, means for positioning a button, 15 and a buttoning device having means for separating the material at opposite edges of a buttonhole and means for engaging under the head of the button and lifting the button in the buttonhole while said edges 20 are separated, said device being constructed to release the material while the button is in lifted position.

21. A buttoning machine having, in combination, means for positioning a button, 25 and a buttoning device having means for engaging and separating the material at opposite edges of a buttonhole, said device having also means for depressing said material relatively to the button head and for 30 lifting the button in the buttonhole to facilitate the disposal of said edges under the button head.

22. A buttoning machine having, in combination, means for relatively positioning a 35 button and a buttonhole fly, and buttoning means movable laterally over the button head in wiping engagement with the buttonhole fly and constructed to depress relatively to the button head the material adjacent to a 40 buttonhole and to lift the button to complete the button operation.

23. A buttoning machine having, in combination, means for positioning a button, and a buttoning device movable laterally over 45 the button head in wiping engagement with a buttonhole fly and constructed to depress relatively to the button head the material adjacent to a buttonhole, said device being constructed also to lift the button relatively 50 to said positioning means to complete the buttoning operation.

24. A buttoning machine having, in combination, means for positioning a button, and a buttoning device movable laterally 55 over the button head in wiping engagement with the buttonhole fly and having means for opening the buttonhole and for depressing relatively to the button head the material at the edges of the buttonhole, said 60 device having flanges constructed to slide under the button head and lift the button relatively to said positioning means to complete the buttoning operation.

25. A buttoning machine having, in combination, means for relatively positioning a 65

button and a buttonhole fly, and a buttoning device movable longitudinally of a buttonhole and having means for moving the button and the buttonhole fly in opposite directions to perform a buttoning operation. 70

26. In a buttoning machine, the combination with means for positioning a button, of a buttoning device movable laterally over the button head to perform a buttoning operation, and means for operating said device, the device being adjustable relatively to its operating means for buttons of different sizes. 75

27. A buttoning machine having, in combination, means for positioning a button, 80 and a buttoning device movable in wiping engagement with the material adjacent to a buttonhole to perform a buttoning operation and having a surface inclined to its direction of movement for depressing said material 85 relatively to the button head, said buttoning device being adjustable to vary the range of depressing action of said inclined surface for buttons of different heights.

28. In a buttoning machine, the combination with means for relatively positioning a button and a buttonhole fly, of a buttoning device movable laterally over the button head to perform a buttoning operation, said device comprising two relatively adjustable 90 portions for performing respectively different operations with respect to the button and the buttonhole fly. 95

29. In a buttoning machine, the combination with means for relatively positioning a button and a buttonhole fly with a buttonhole over the button, of a buttoning device movable laterally over the button head to perform a buttoning operation, said device comprising a front portion shaped to enter 100 the buttonhole and to depress the material adjacent to the buttonhole relatively to the button head and a rear portion for engagement under the button head, the front portion being adjustable relatively to the rear 105 portion to conform to differences in the height of different buttons. 110

30. In a buttoning machine, the combination with means for relatively positioning a button and a buttonhole fly, of a buttoning device movable laterally over the button head to perform a buttoning operation, said device comprising a front portion shaped for engagement with the buttonhole fly over the button head to depress the material at 115 the sides of a buttonhole relatively to the button head and a rear portion for engagement under the button head, the front portion being adjustable relatively to the rear portion about an axis positioned substantially between the two portions to conform 120 to differences in the height of different buttons. 125

31. In a buttoning machine, the combination with a button supporting fork, of a but- 130

- toning device movable laterally over a button in said fork to perform a buttoning operation, said device comprising a front portion for engagement with the buttonhole fly
- 5 over the top of the button head and a rear portion for engagement under the button head, the front portion being adjustable relatively to the rear portion to conform to differences in the height of different buttons.
- 10 32. A buttoning machine having, in combination, means for positioning a button, and buttoning means mounted for swinging movement into position over the button head to perform a buttoning operation with respect to the button.
- 15 33. A buttoning machine having, in combination, means for positioning a button, and buttoning means mounted for swinging movement laterally of the button head from
- 20 a position at one side of the button and constructed to perform a buttoning operation with respect to the button through said movement.
- 25 34. A buttoning machine having, in combination, means for relatively positioning a button and a buttonhole fly, and means for performing a buttoning operation with respect to said button and buttonhole fly, said last named means being mounted for swinging movement into engagement with the buttonhole fly in a direction lengthwise of a buttonhole.
- 30 35. A buttoning machine having, in combination, means for relatively positioning a button and a buttonhole fly, and a buttoning device pivoted to swing longitudinally of a buttonhole in wiping engagement with the material at opposite sides of the buttonhole to perform a buttoning operation.
- 35 36. A buttoning machine having, in combination, a button positioning fork, and buttoning means movable longitudinally of said fork in engagement with a buttonhole fly to perform a buttoning operation with respect to a button in said fork.
- 40 37. A buttoning machine having, in combination, a button positioning fork, and buttoning means movable rearwardly along said fork in engagement with a buttonhole fly to dispose the material adjacent to a buttonhole in buttoned relation to a button in the fork.
- 45 38. A buttoning machine having, in combination, means for positioning a button, buttoning means movable in wiping engagement with a buttonhole fly to perform a buttoning operation with respect to the button, and means for restraining the buttonhole fly from moving in the direction of movement of the buttoning means.
- 50 39. A buttoning machine having, in combination, means for positioning a button, buttoning means movable longitudinally of a buttonhole in a buttonhole fly to dispose the material at the sides of the buttonhole in buttoned relation to the button, and
- means for engaging the buttonhole fly in front of the buttonhole to restrain it from moving in the direction of movement of the buttoning means.
40. A buttoning machine having, in combination, means for positioning a button, buttoning means movable in wiping engagement with a buttonhole fly to perform a buttoning operation with respect to the button, means for engaging the buttonhole fly to hold it against the drag of the buttoning means, and means for causing the engagement of said last named means with the buttonhole fly prior to the operation of the buttoning means on the fly. 70
41. A buttoning machine having, in combination, buttoning means for performing a buttoning operation with respect to a button and a buttonhole fly, and means for clamping the buttonhole fly at one end of a buttonhole with yielding pressure to determine its position during the operation of the buttoning means. 75
42. A buttoning machine having, in combination, buttoning means for performing a buttoning operation with respect to a button and a buttonhole fly, a clamp member movable into engagement with the buttonhole fly at one end of a buttonhole, and means for operating said clamp member including portions relatively movable against yielding resistance to cause said member to engage the fly with yielding pressure. 80
43. A buttoning machine having, in combination, a button positioning fork, buttoning means movable lengthwise of the fork in engagement with a buttonhole fly to perform a buttoning operation, and means for clamping the buttonhole fly on the fork to hold it against the drag of the buttoning means. 85
44. A buttoning machine having, in combination, a button positioning fork, buttoning means movable lengthwise of the fork in engagement with a buttonhole fly to perform a buttoning operation, a clamp member movable into engagement with the buttonhole fly to restrain it from movement in the direction of movement of the buttoning means, and operating means constructed to move said clamp member to operative position prior to the operation of the buttoning means on the fly. 90
45. A buttoning machine having, in combination, means for positioning a button, and a buttoning device movable in engagement with a buttonhole fly to dispose the material adjacent to a buttonhole in buttoned relation to the button, said device having means for engaging in one end of the buttonhole to position the buttonhole initially with reference to the button. 95
46. A buttoning machine having, in combination, means for positioning a button, and a buttoning device movable longitudinally of the buttonhole to position the buttonhole initially with reference to the button. 100
47. A buttoning machine having, in combination, a button positioning fork, buttoning means movable lengthwise of the fork in engagement with a buttonhole fly to perform a buttoning operation, and means for clamping the buttonhole fly on the fork to hold it against the drag of the buttoning means. 105
48. A buttoning machine having, in combination, a button positioning fork, buttoning means movable lengthwise of the fork in engagement with a buttonhole fly to perform a buttoning operation, a clamp member movable into engagement with the buttonhole fly to restrain it from movement in the direction of movement of the buttoning means, and operating means constructed to move said clamp member to operative position prior to the operation of the buttoning means on the fly. 110
49. A buttoning machine having, in combination, means for positioning a button, and a buttoning device movable in engagement with a buttonhole fly to dispose the material adjacent to a buttonhole in buttoned relation to the button, said device having means for engaging in one end of the buttonhole to position the buttonhole initially with reference to the button. 115
50. A buttoning machine having, in combination, means for positioning a button, and a buttoning device movable in engagement with a buttonhole fly to dispose the material adjacent to a buttonhole in buttoned relation to the button, said device having means for engaging in one end of the buttonhole to position the buttonhole initially with reference to the button. 120
51. A buttoning machine having, in combination, means for positioning a button, and a buttoning device movable in engagement with a buttonhole fly to dispose the material adjacent to a buttonhole in buttoned relation to the button, said device having means for engaging in one end of the buttonhole to position the buttonhole initially with reference to the button. 125
52. A buttoning machine having, in combination, means for positioning a button, and a buttoning device movable longitudinally of the buttonhole to position the buttonhole initially with reference to the button. 130

nally of a buttonhole in a buttonhole fly to perform a buttoning operation with respect to said button, said device having means for engaging in the buttonhole to effect a preliminary positioning movement of the material adjacent to the buttonhole.

47. A buttoning machine having, in combination, means for positioning a button, and buttoning means movable relatively to the button to perform a buttoning operation with respect to said button, said buttoning means being constructed to engage in one end of a buttonhole in a buttonhole fly to effect a preliminary positioning movement of the material adjacent to the buttonhole and then to dispose said material in buttoned relation to the button.

48. A buttoning machine having, in combination, means for positioning a button, and a buttoning device movable relatively to the button to perform a buttoning operation with respect to said button, said device having means for engaging in one end of a buttonhole to position the buttonhole relatively to the button and means for opening the buttonhole and depressing the material at the edges of the buttonhole relatively to the head of the button.

49. A buttoning machine having, in combination, means for positioning a button, a buttoning device movable in engagement with a buttonhole fly to dispose the material adjacent to a buttonhole in buttoned relation to the button, said device having means for engagement in the buttonhole with the material at one end of the buttonhole to position the buttonhole relatively to the button, and means for engaging the buttonhole fly adjacent to the other end of the buttonhole to hold it against the pull of said buttoning device.

50. A buttoning machine having, in combination, means for positioning a button, buttonhole fly positioning means arranged to engage in a buttonhole to position the buttonhole relatively to the button, buttoning means movable lengthwise of the buttonhole, and means for withdrawing said buttonhole fly positioning means from the buttonhole to permit the buttoning means to operate.

51. A buttoning machine having, in combination, means for positioning a button, a member arranged to engage in a buttonhole in a buttonhole fly to position the buttonhole over the head of the button, buttoning means movable lengthwise of the buttonhole to dispose the material adjacent to the buttonhole in buttoned relation to the button, and means for withdrawing said member from the buttonhole to permit said buttoning means to operate.

52. A buttoning machine having, in combination, means for positioning a button,

a member arranged to engage in one end of a buttonhole in a buttonhole fly to position the buttonhole relatively to the button, buttoning means movable in engagement with the buttonhole fly to dispose the material adjacent to the buttonhole in buttoned relation to the button, means for withdrawing said member from the buttonhole to permit the buttoning means to operate, and means for clamping the buttonhole fly adjacent to the buttonhole prior to the withdrawal of said member.

53. A buttoning machine having, in combination, a button receiving fork, a member extending in transverse relation to said fork for engagement in a buttonhole to position the buttonhole relatively to the button, means for performing a buttoning operation with respect to the button while the button is positioned in said fork, and means for withdrawing said member from the buttonhole to permit said operation to be performed.

54. In a buttoning machine, the combination with a button receiving fork, of a buttonhole fly positioning member arranged to engage in a buttonhole, means for clamping the buttonhole fly to position it during the buttoning operation, and means for withdrawing said member from the buttonhole after the buttonhole fly has been clamped.

55. A buttoning machine having, in combination, a forwardly directed button positioning fork, a member projecting upwardly at the rear of a button in said fork for engagement in a buttonhole to position the buttonhole fly over the button, buttoning means movable rearwardly over the button in said fork, and means for withdrawing said member from the path of movement of the buttoning means.

56. A buttoning machine having, in combination, a forwardly directed button positioning fork, a member projecting upwardly at the rear of a button in said fork for engagement in a buttonhole to position the buttonhole fly over the button, buttoning means movable rearwardly over the button in said fork, means for withdrawing said member from the path of movement of the buttoning means, and means for clamping the buttonhole fly in front of the button prior to the withdrawal of said member.

57. A buttoning machine having, in combination, button positioning means arranged to receive a button in position for a buttoning operation when the work is initially presented to the machine, means for performing a buttoning operation with respect to the button, and means for ejecting the button from said positioning means after the buttoning operation has been performed.

58. A buttoning machine having, in combination, a button positioning fork, means

- for performing a buttoning operation with respect to a button in said fork, and means movable longitudinally of the fork for ejecting the work from the machine after the buttoning operation has been performed.
59. A buttoning machine having, in combination, a button positioning fork, means for performing a buttoning operation with respect to a button in said fork, and means 10 for engaging the button piece adjacent to the fork to eject the work from the machine after the buttoning operation has been performed.

60. A buttoning machine having, in combination, a plurality of sets of operating instrumentalities for performing buttoning operations with respect to a plurality of buttons, said sets being relatively adjustable about a single axis to conform to differences 20 in the spacing of the buttons on different pieces of work.

61. In a buttoning machine, a substantially horizontal series of button positioning forks, said forks being relatively adjustable 25 about a substantially upright axis to conform to differences in the spacing of the buttons on different pieces of work.

62. A buttoning machine having, in combination, means for positioning a row of buttons, a plurality of buttoning devices mounted to swing transversely of the row of buttons to perform buttoning operations with respect to said buttons, and means for operating said devices to perform a plurality 35 of buttoning operations substantially simultaneously.

63. A buttoning machine having, in combination, a plurality of button positioning forks, a bar movable into position in front 40 of the buttons in said forks to clamp a buttonhole fly upon the forks, a plurality of buttoning devices movable rearwardly into engagement with the buttonhole fly to dispose the material adjacent to the buttonholes in buttoned relation to the buttons, and means for operating said devices to perform a plurality of buttoning operations 45 substantially simultaneously.

64. A buttoning machine having, in combination, means for positioning a button, means for clamping a buttonhole fly to position it relatively to the button, means for performing a buttoning operation with respect to the button, means for ejecting the 55 work from the machine, and means for operating said clamping means to release the work prior to the operation of said ejecting means.

65. A buttoning machine having, in combination, means for positioning a button, and buttonhole fly engaging means movable to dispose the material adjacent to a buttonhole in buttoned relation to the button, said buttonhole fly engaging means being con-

structed to lift the button to facilitate the 65 disposal of said material under the button head.

66. A buttoning machine having, in combination, means for positioning a button, and buttoning means arranged to depress relatively to the button the material adjacent to a buttonhole and to raise the button to facilitate the disposal of said material under the button head.

67. A buttoning machine having, in combination, button positioning means, button-hole fly engaging means, and means for performing a buttoning operation by relative movement of the buttonhole fly and the buttonhole fly engaging means with said last named means in wiping engagement with the fly at opposite sides of a buttonhole.

68. A buttoning machine having, in combination, button positioning means, button-hole fly engaging means, and mechanism for 85 moving said buttonhole fly engaging means in a curved path laterally of the button head first into engagement with the buttonhole fly and then along the surface of the fly to dispose the material adjacent to a buttonhole in buttoned relation to a button.

69. A buttoning machine having, in combination, means for positioning a button, buttonhole fly engaging means, and mechanism for moving said buttonhole fly engaging means along the surface of the buttonhole fly at opposite sides of a buttonhole to dispose the material adjacent to the buttonhole in buttoned relation to the button.

70. In a buttoning machine, the combination with button positioning means, of buttonhole fly engaging means, and mechanism for effecting relative movement of said buttonhole fly engaging means and a buttonhole fly longitudinally of a buttonhole to open 100 the buttonhole.

71. A buttoning machine having, in combination, a forwardly directed button positioning fork, a member projecting upwardly at the rear of a button in said fork for engagement in a buttonhole to position the buttonhole fly, and means for performing a buttoning operation with respect to said button and buttonhole while the button is positioned in said fork.

72. A buttoning machine having, in combination, means for positioning a button, and buttonhole fly engaging means movable in wiping engagement with the material adjacent to a buttonhole at the opposite sides 110 of the buttonhole to dispose the material in buttoned relation to the button.

73. A buttoning machine having, in combination, means for positioning a button, a buttoning device having diverging portions 125 for spreading the opposite edges of a buttonhole and other portions for depressing said separated edges over the button head,

and means for moving said device laterally of the button head to perform the buttoning operation.

74. A buttoning machine having, in combination, means for positioning a button, a buttoning device having diverging portions for spreading the opposite edges of a buttonhole, said device having an opening between said diverging portions to receive the button head, and means for moving said device laterally of the button head to perform the buttoning operation.

75. A buttoning machine having, in combination, means for positioning a button, and buttoning means movable laterally of the button head to perform a buttoning operation and having portions arranged to slide under the button head at opposite sides of the button between the button head and the buttonhole fly.

76. A buttoning machine having, in combination, means for positioning a button, a buttoning device having means for depressing relatively to the button head the material at opposite sides of a buttonhole and flanges arranged to slide under opposite sides of the button head, and means for moving said device laterally of the button head to perform the buttoning operation.

77. A buttoning machine having, in combination, means for positioning a button, a buttoning device having an opening to receive the button head and also means for depressing the material at opposite sides of a buttonhole over the button head and for tucking it under the button head, and means for moving said device laterally of the button head to perform the buttoning operation.

78. A buttoning machine having, in combination, means for positioning a row of buttons, buttoning means mounted for movement transversely of the row of buttons in wiping engagement with the buttonhole fly to perform buttoning operations with respect to said buttons, and means for operating said buttoning means.

79. A buttoning machine having, in combination, means for positioning a row of buttons, a plurality of buttoning devices mounted for movement transversely of the row of buttons and laterally with respect to the button heads to perform buttoning operations with respect to the buttons, and means for operating said devices.

80. A buttoning machine having, in combination, a plurality of forks arranged to position a row of buttons, means for positioning a buttonhole fly with the buttonholes over the buttons, a plurality of buttoning devices movable lengthwise of said forks to dispose the material of the buttonhole fly

in buttoned relation to the buttons, and means for operating said devices substantially simultaneously.

81. A buttoning machine having, in combination, a plurality of forks arranged to position a row of buttons, means for positioning a buttonhole fly and for clamping it in front of the buttons, and buttoning means movable rearwardly lengthwise of the forks for disposing the material of the buttonhole fly in buttoned relation to the buttons.

82. A buttoning machine having, in combination, buttonhole fly engaging means, button positioning means, and mechanism for effecting relative movement of said means to cause the buttonhole fly engaging means to force the material adjacent to a buttonhole over the head of a button and to move under the head to dispose said material in buttoned position, said button positioning means being organized to permit the button to be lifted by the action of the buttonhole fly engaging means as said means moves under the button head.

83. A buttoning machine, having in combination, buttoning means movable to force the material adjacent to a buttonhole over the head of a button and to dispose the material under the head, and means for supporting the button in such manner as to leave the button free to be lifted by the buttoning means.

84. A buttoning machine having, in combination, buttoning means movable to force the material adjacent to a buttonhole over the head of a button and movable under the button head to dispose the material in buttoned relation to the button, and means for supporting the button in such manner as to permit the button to be lifted by the buttoning means as it moves under the button head.

85. A buttoning machine having, in combination, buttoning means movable under the edges of a button head at opposite sides of the button to dispose the material adjacent to a buttonhole in buttoned relation to the button, and means for supporting the button in such manner as to permit the button to be lifted by the buttoning means.

86. In a buttoning machine, the combination with means for performing a buttoning operation, of means for discharging the work from the machine by engagement with the button after the buttoning operation is performed.

In testimony whereof I have signed my name to this specification.

LEWIS J. BAZZONI.
